A. C. HULBERT

ELECTRIC STEAM RADIATOR

Filed Sept. 8, 1921

UNITED STATES PATENT OFFICE.

ANSEL C. HULBERT, OF SAN CARLOS, CALIFORNIA.

ELECTRIC STEAM RADIATOR.

Application filed September 8, 1921. Serial No. 499,290.

To all whom it may concern:

Be it known that I, ANSEL C. HULBERT, a citizen of the United States, residing at San Carlos, in the county of San Mateo, State of California, have invented a new and useful Electric Steam Radiator, of which the following is a specification in such full and clear terms as will enable those skilled in the art to construct and use 10 the same.

This invention relates to an electric steam radiator and its object is to provide an automatic steam radiator which will have a receptacle for the water below the body of 15 the radiator so connected thereto as to keep the radiator properly drained at all times, and thereby completely insure the circulation of steam from the boiler through the heat radiating coils and back to the boiler 20 when condensed, thereby effecting a satisfactory transfer of heat from the steam to the room in which the heater is placed.

Another object of the invention is to so position the water glass and automatic cut- 25 out as to make them easy of access.

A further object of the invention is to provide a special coil which will give off sufficient heat to prevent the water in the radiator from freezing, if the radiator is 30 used in a country cold enough to be likely to freeze it up completely when not in ordinary use.

Other objects of the invention will appear as the description proceeds.

35 An embodiment of the invention is shown in the accompanying drawings in which the same reference numeral is applied to the same portion throughout, but I am aware that there may be modifications 40 thereof.

Fig. 1 is a side elevation of the complete radiator.

Fig. 2 is an end view of the same.

45 Fig. 3 is a sectional view on a slightly larger scale of the boiler and connection of the radiator, also showing the regulator in section.

Fig. 4 is a diagrammatic view of the electrical connections, and

50 Fig. 5 shows the face plate of the boiler with the electric circuit plugs projecting therefrom.

The radiator comprises two end sections 1 and 2 which have legs 3 and 4 mounted

55 on castors 5 and 6 in order that the radiator may be conveniently moved around the

room. There is an air valve 7 on the section 1, and safety valve 8 on the section 2. While these sections are separated by a plurality of sections 9 to 11 inclusive, the number of sections may be increased or diminished at will. 60

The end section 1 has a hole in its lowest part to receive the pipe 12. This pipe is screwed thereinto and has the union 13 for connecting it to a nipple 14 screwed into the lowest part of the rectangular boiler 15.

At its opposite end the boiler has a larger pipe 16 screwed thereinto and which pipe screws into a steam casing 17 having a 70 flange 18 for connection with the flange 19 on the nipple 20 which is screwed into the radiator section 2.

It will be understood by those skilled in the art that the radiator sections are suitably bolted together to prevent the escape 75 of steam at their joints.

The boiler has four holes to receive the terminal receptacles 21 to 24 inclusive, each of which plugs carry a heating coil 25. 80 Mounted on the top of the casing 17 is a nipple 26 which in turn carries the casing 27 which forms the chamber for the operation of the diaphragm regulator 28. The diaphragm is held against the casing 27 by 85 means of bolts 29, and another casing 30 encloses the diaphragm and forms the support for a pin 31 bearing upon the diaphragm.

The pin 31 bears upon a lever 32 which 90 in turn has a cross-bar 33 bearing upon the two levers 34, 35. The levers 34, 35 are supported by flexible springs 36 screwed to a block 37 insulated from the rest of the structure by means of the pad of insulating material 38.

At the top of the regulator there is a clamping member 39 which has an insulating fibre 40 secured within the same and within which is the block 41 for holding the 100 adjustable contact screw 42. On the one side of the casing 17 there are two elbows 43, 44 which form the support for the water glass 45 to determine the level of the water in the boiler.

A cable 46 extends from the face plate of the boiler to the regulating apparatus for varying the current to maintain a given radiator temperature. 105

In order to prevent the regulating apparatus from being tampered with there is provided a cover plate 47. Current is sup-

plied to the apparatus through the cable 48 and plug 49, which plug may be connected with either of the terminal receptacles 50 or 51. The terminal receptacle 50 is attached to the heating terminal receptacle 22, while the terminal receptacle 51 is attached to the heating terminal receptacle 21. The terminal receptacle 50 supplies one of the coils 25 with a sufficient amount of current 10 to prevent the water in the radiator from freezing, but not sufficient to make necessary the operation of the regulator.

When more heat is required the plug 49 is changed to the terminal receptacle 51, 15 whereupon current is supplied to the three coils 25 as illustrated in Figure 4, in which the numerals 52, 53 indicate the current supply wires, 54 a wire extending to the block 37, 55 a wire extending from a contact on the block 37 to one of the coils 25, 56 a wire extending from the other connecting screw 42 under the lever 35 to another of the coils 25, while wires 57, 58 serve to connect the other terminal of the two coils 25 25 with the feed wire 53.

The result of the foregoing construction is that three of the coils 25 will receive current in parallel when the plug 49 is attached to the plug 51, and if the pressure gets high 30 enough the diaphragm will disconnect one or both of the coils 25 receiving current from the two wires 55, 56, the load being broken on one coil first thereby reducing the load and then upon the other coils to avoid 35 undue sparking, while at all times when the power is connected with the apparatus one of the coils give off some heat from the cur-

rent supplied thereto, regardless of the operation of the regulating apparatus.

What I claim is as follows, but various 40 modifications may be made in the construction shown in the drawings and above particularly described form, within the purview of my invention:

1. An electric steam radiator, comprising a 45 plurality of connected radiator sections, legs to support the radiator sections above the floor level, and means for regulating the current supplied to the heating elements whereby the danger of exceeding a safe 50 pressure within the radiator is avoided one of said elements being unregulated to keep the radiator warmer than the atmosphere when connected.

2. An electric steam radiator comprising 55 a plurality of radiator sections secured together, legs for supporting said radiator sections above the level of the floor, a closed water receptacle supported between the legs, 60 pipes connecting the water receptacle with the lower portion of the radiator sections, a plurality of electric heating units in the water receptacle, and a steam pressure operated electric switch for regulating the current supplied to certain of the heating elements in the water receptacle whereby the production of an excessive pressure within the radiator is prevented one heating element being without regulation to keep the heater warm whenever it is connected. 65

In testimony whereof I have hereunto set my hand this 30th day of August A. D. 1921.

ANSEL C. HULBERT.
